(No Model.)

O. B. ROWLETT & W. C. SHOEMAKER.
FENCE MACHINE.

No. 352,892.

Patented Nov. 16, 1886.

UNITED STATES PATENT OFFICE.

OLIVER B. ROWLETT AND WILLIAM C. SHOEMAKER, OF RICHMOND, IND.

FENCE-MACHINE.

SPECIFICATION forming part of Letters Patent No. 352,892, dated November 16, 1886.

Application filed September 7, 1886. Serial No. 212,967. (No model.)

To all whom it may concern:

Be it known that we, OLIVER B. ROWLETT and WILLIAM C. SHOEMAKER, citizens of the United States, and residents of Richmond, in the county of Wayne and State of Indiana, have invented certain new and useful Improvements in Fence-Machines, of which the following is a specification.

Our invention relates to fence-machines which are employed to twist wires around slats, building the fence in position for use, the various objects of which will be more fully set forth in the description of the accompanying drawings, making a part of this specification, in which—

Figure 1 is a perspective view of our improvement in position for use. Fig. 2 is a side elevation of the supporting-frame. Fig. 3 is a section of the twisting device on line $x-x$, Fig. 20. 1. Fig. 4 is a perspective view of the frame-bracket; Fig. 5, a sectional elevation of the adjusting-clamp. Fig. 6 is a top plan view of the top gage and suspending-clamp. Fig. 7 is a bottom perspective view of the same. Fig. 25 8 is an end view of the upright frame and adjustable gearing. Fig. 9 is a perspective view of the top gage. Fig. 10 is a perspective view of the adjustable tubular wire eye. Fig. 11 is a similar view of a bracket to which said eye is attached. Fig. 12 is a plan view of the frame-bracket for connecting the supporting-frame sill, ground-wheels and upright-frame brace.

1 represents posts or uprights forming an open frame upon which the intermediate and twisting gears are mounted.

2 represents the base or sill of the supporting-frame, which is mounted on ground-wheels 3.

4 represents a segmental brace adjustably connected to the upright frame 1.

5 represents a pivot hinging to sill 2 of the upright frame.

6 represents the frame-bracket, by means of which sill 2, segment 4, and ground-wheel 3 are connected together, there being a bracket, 6, at each end of the sill or frame, one being the counterpart of the other.

7 represents a recess formed by ribs 8, into which one end of sill 2 fits.

50 9 represents a hole through which the cen-

tering stud-bolt 10 passes. This bolt secures the sill 2 to bracket 6, and extends sufficiently through said sill and bracket to form a stud on which ground-wheel 3 journals. 11 represents a recess for securing one end of segment 4 to said bracket.

12 represents flanges or ribs against which the edges of the segment abut to hold it firmly in position. 13 represents a bolt-hole through which a bolt passes, rigidly connecting said segments to said brackets.

The supporting-frame is composed of sill 2, segment 4, and the two brackets 6, and the four bolts uniting the parts together.

In order that the loom or upright frame may be adjusted at different angles from the vertical, we provide the following adjusting devices: Upright frame 1 is hinged by pivot 5 to the supporting-frame on which it normally turns. 14, Fig. 5, represents a through-bolt passing through frame-piece 1. 15 represents a clamp pivoted to said frame 1. 16 represents a set-nut engaging the threads on bolt 14.

Segment 4 plays between post 1 and clamp 15, and is secured thereto by means of nut 16, which when turned draws clamp 15 against the segment 4 and post 1. It is desirable to have the tops of the slats even. To obtain this result we have employed an adjustable gage-plate, 17, which is adjustably secured upon bracket 18 by means of a slot, 19, pierced in the shank of the gage-plate. 20 represents a slot in said bracket 18, through which slot a bolt, 23, passes. The foot or L part of this gage-plate 17 serves as a stop against which the top of the slat rests.

In order that the slat may be readily inserted and held in this position, we provide spring clamp-arms 21, which are secured to the loom-frame at one end and extend outward in a curved form, so as to form a clasp at the throat formed by the reversed curved fingers 21, between which the slat is thrust and held by the retractile force of the spring. Thus the slats are readily inserted and held at a uniform plane at the top until the wires are twisted to hold them permanently, and readily released as the machine is drawn backward.

In order that the ends of the brackets 6 of the supporting-frame may not catch against

100

the slats, the free ends 22 of said brackets are curved or bent outward.

We have devised the following instrumentalities for mounting and driving the twisting-disks: 24 represents the twisting-gear provided with a cylindrical boss or shaft, 25, which journals in bracket 26 on post 1. 41, Fig. 3, represents a collar suitably connected to the hub of the twisting-wheel and overlapping the bracket, and thus securing the twisting-wheel against the face of the bracket and allowing it to revolve within the periphery of the rim therein. 27, Fig. 11, represents a slotted bracket rigidly secured to the face of the twisting-gears. 28 represents adjustable eyes, each having an elongated slotted shank, through which is passed a clamping-bolt, 29, which may likewise secure bracket 27 to twisting-disk 24. 30 represents a semi-tubular extension of the eyes passing through the slot in bracket 27, so as to form an elongated bearing to support the wires, which are twisted by the revolution of disk 24. 40 represents an enlarged portion of the slot near the end 25 where the wire presses in working, and through which knots in the wire may be passed without cutting the wire, as is required in most devices heretofore made. In order that these twisting-disks may be adjusted vertically, we 30 provide a series of transmitting-gears, 31, which are journaled to slotted bracket 37, so as to be laterally adjustable therein. Fig. 1 shows the disks 24 set farthest apart. Fig. 8 shows transmitters 31 set to the right to bring the 35 twisting-disks nearer together, hence diminishing the distance between the wires supporting the slats. The transmitters 31, having teeth on their peripheries of the same pitch as disks 24, allow of this adjustment, and the 40 entire series are driven by a single crank, 34, which drives bevel 35, journaled on one end of the crank-shaft and meshing with the bevel-teeth 36, formed at the periphery of one of the transmitters. The object of these bevels is to 45 allow crank 34 to revolve in a plane parallel with the vertical plane of the fence.

By using intermediate transmitters, 31, and the twisting-disks 24, we accomplish two results—first, these wheels are lighter than when 50 large twisting-disks are employed with peripheral teeth transmitting motion from one to the other; second, it allows of their being vertically adjusted to readily regulate the distance between the wires.

55 The various devices herein shown are simple, cheap, and effective in their operation. The slotted eye 28 allows a ready adjustment between the wires to accommodate different thicknesses of slats. The semi-tubular extension 30 holds and delivers the wires in a better manner than other devices.

Our entire machine is light, strong, and durable.

We claim—

1. The combination, with an upright frame 65 carrying twisting devices, of the sill 2, pivoted to the lower end of said frame, the segmental brace 4, adjustable on said frame, the ground-wheels 3, and the brackets 6, connecting said wheels and brace to the sill, substantially as 70 described.

2. The combination of the twisting-frame 1, the pivoted sill 2, having wheels 3, the segmental brace 4, pivoted clamp 15, through-bolt 14, and set-nut 16, substantially as described. 75

3. The combination of the twisting-frame 1, pivoted sill 2, adjustable segment-brace 4, and the brackets 6, having recesses 7 and 11, for connecting the sill and brace, substantially as 80 described.

4. The combination of the upright wire-twisting frame, the spring-clamp 21, and gage 17, for suspending the slats at their top in a uniform plane, substantially as specified.

5. In combination with the top of the up- 85 right frame, the vertically-adjusting gage 17, and spring-clamps 21, located beneath said gage, substantially as specified.

6. The twisting-eyes 28, provided with the semi-tubular extension 30, substantially as 90 specified.

7. The twisting eye 28, provided with the enlargement in its slot for the passage of the knots in the wires, substantially as specified.

8. In combination with the twisting-disk 95 24, the slotted bracket 27, and the twisting-eyes 28, having an elongated slotted shank, and a semi-tubular extension, 30, substantially as described.

9. The combination of the upright frame 1, 100 slotted brackets 26, twisting-disks 24, slotted brackets 27, eyes 28, having semi-tubular extensions 30, and the bolts 29, substantially as described.

10. A wire-twisting loom composed of the 105 vertical frame 1, the alternate series of twisting-disks 24, having vertically-adjustable bearings, and provided with teeth on their peripheries, and the series of transmitters 31, arranged alternately between the twisters, provided with 110 laterally-adjustable bearings, and driven by a crank and bevel-pinions, substantially as specified.

In testimony whereof we have hereunto set our hands.

OLIVER B. ROWLETT.
